(57) **CLAIM**

The ornamental design for a pontoon boat, as shown and described.

DESCRIPTION

FIG. 1 is a front isometric view of a pontoon boat according to the present invention.

FIG. 2 is a front isometric view of the pontoon boat of FIG. 1 with the seating platform and associated seat exploded upwards.

FIG. 3 is a rear isometric view of the pontoon boat of FIG. 1.

FIG. 4 is a rear isometric view of the pontoon boat of FIG. 2 with the seating platform and associated seat exploded upwards.

FIG. 5 is a top view of the pontoon boat of FIG. 1. No bottom view is provided, as no claim is made to the appearance of the bottom of the pontoon boat.

FIG. 6 is a first side view of the pontoon boat of FIG. 1.

FIG. 7 is an opposite side view of the pontoon boat of FIG. 1.

FIG. 8 is a front view of the pontoon boat of FIG. 1; and, FIG. 9 is a rear view of the pontoon boat of FIG. 1.

The broken lines depict portions of the pontoon boat that form no part of the claimed design.
